WALL CONSTRUCTION

Charles R. Emery, Dearborn, Mich.

Application March 4, 1938, Serial No. 193,979

15 Claims. (Cl. 72—39)

This invention relates to the construction of walls and has for its object to provide a wall composed of blocks constructed and arranged to provide a space therein in which air is free to circulate whereby moisture will not penetrate through the wall. The outside surface is weather resistant and the inside may be finished as by the direct application of a coat of plaster or paint thereto.

More specifically, the object is to provide a wall composed of blocks assembled in courses and having communicating spaces whereby air may circulate both vertically and longitudinally of the wall, without interruption at corners, windows or doors. According to this construction, a horizontal line passing through the blocks at any point in the wall will pass through an air space.

Another object is to provide a wall composed of blocks constructed and arranged in courses whereby they form a zigzag channel extending lengthwise of each course, the blocks of alternate courses being staggered whereby the zigzag channel of any course is non-parallel with the channels of a next adjacent course. In combination with such an arrangement, the invention provides a half-block of special form and adapted for use at the corners of angularly disposed wall portions to provide communication between the zigzag channels of such portions, and also adapted for use adjacent window and door frames to provide communication between the zigzag channels on opposite sides of such frames.

In the accompanying drawing

Figs. 1 and 2 are perspective views of a wall; Fig. 3 is a horizontal section of the wall, and Fig. 4 is a horizontal section illustrating a window assembled in the wall.

The main portion of the wall is formed of courses of blocks. Each course is composed of inner blocks 1 and outer blocks 2, with both the inner and outer blocks having parallel top and bottom surfaces extending perpendicular to their exposed faces. The blocks 1 and 2 are identical as to shape and are formed with V-shaped projections 3. The inner blocks are staggered relative to the outer blocks whereby the projections thereon extend into the angles formed by the projections on the outer blocks and vice versa, the projections on the inner and outer blocks being relatively spaced whereby they form a zigzag channel 4. The projections 3, on both the inner and outer blocks, have openings 5 extending vertically therethrough thus forming blocks of triangular horizontal section.

As may be observed by comparing Figures 1

and 2, the courses of blocks are staggered. The projections on the inner blocks of one course overlie the projections on the outer blocks of the course below and are mortar bonded thereto. Likewise, the outer blocks of said course overlie the projections on the inner blocks of the course below and are mortar bonded thereto. The spaced apart inner and outer blocks of each course are thus firmly united in the wall structure, and although the zigzag channels of alternate courses are non-parallel, they communicate one with another.

At the corner of the wall is provided a corner piece 6 having a shoulder 7 mortar bonded to the adjacent outer block 2 of one portion of the wall and a tapered end 8 similarly bonded to the adjacent outer block 2 of the other portion of the wall. The tapered end 8 co-operates with the adjacent inner block 1 and provides a continuation 9 of the adjacent zigzag channel 4. A half-block 10, composed of two angularly disposed legs 11 and 12, has its longer leg 12 bonded by mortar to the adjacent inner blocks 1 and its shorter leg 11 co-operates with the adjacent outer block 2 to provide a continuation of the adjacent channel 4 to connect it with the continuation 9 and the channel 4 in the other portion of the wall. As a result, air may circulate around the corner.

It will also be noted upon comparing Figs. 1 and 2 that the corner construction above described is present in the two different courses shown, and that the arrangement in one course is opposite to that in the other course.

In Fig. 4 the half-block 10 is illustrated in conjunction with a window frame 14 having vertically sliding sash 15 equipped with the usual counter weights 16. The longer leg 12 provides an abutment for the frame whereas the shorter leg 11 terminates in spaced relation to the frame. The space thus provided accommodates the sash counter weights and also provides for communication between the zigzag channels on opposite sides of the frame with those extending above and below the frame.

The arrangement of the blocks in conjunction with door frames is similar to that above described with the exception that the counter weights will be absent.

Having thus described the invention what is claimed as new, is:

1. A corner construction for a wall built of blocks arranged in courses one above the other comprising hollow blocks, one of said blocks constituting an outside corner piece and having a projection extending rearwardly of the exposed

- faces thereof, and two additional blocks having faces which meet to form the inside corner and each having a projection spaced from the projection of said outside corner piece to form an air space around said corner.
5. A corner construction for a wall built of blocks arranged in courses one above the other comprising hollow blocks, one of said blocks constituting an outside corner piece and having a projection extending rearwardly of the exposed faces thereof, one of said exposed faces being longer than the other thereof, that part of the projection extending rearwardly of the longer of said faces forming an acute angle therewith, 10 and two additional blocks having faces which meet to form the inside corner of the wall and each having a projection extending from the exposed face thereof, both projections of said two blocks being spaced from the projection of 15 said outside piece with the projection of one of said two blocks paralleling that part of the projection of the outside block which forms an acute angle with the longer exposed face thereof.
6. A corner construction for a wall built of blocks arranged in courses one above the other comprising hollow blocks, one of said blocks constituting an outside corner piece and having a projection extending rearwardly of the two exposed faces thereof, one of said exposed faces 20 being longer than the other, that part of the projection which extends from one end of said longer face forming an acute angle therewith, that part of said projection which extends from the shorter face thereof forming a right angle therewith whereby said corner piece has four sides, and two additional blocks having faces which meet 25 to form the inside corner of the wall and each having projections extending rearwardly therefrom, the projections of both of said two blocks being spaced from the projection of said outside corner space to form an air space between the 30 inside and outside blocks, one of said two blocks being approximately twice the length of the other thereof with a length of the projection of the longer one thereof paralleling that part of the projection of the outside block which forms an 35 acute angle with the longer face of said outside block.
7. A corner construction according to claim 1 in combination with side walls for each of said courses composed of inner and outer blocks each 40 having projections extending into the wall from the exposed surfaces thereof, the interior one of said blocks being staggered longitudinally and spaced laterally with respect to the exterior ones thereof thereby continuing the air space around 45 said corner along each side wall therefrom.
8. A wall construction comprising a plurality of blocks of triangular horizontal cross-section laid in courses one above the other, the blocks of each course being horizontally staggered from 50 inside to outside and laterally spaced thereby forming a continuous air passage, and a corner construction for the wall comprising a block having four vertical sides two of which form a right angle for the outside corner of the wall and 55 two of which form an acute angle, an inside horizontally triangular block having one apex at the inside corner of the wall and a block of the shape of substantially half a triangle having one leg meeting said apex, said four sided block 60 being horizontally spaced from the other two corner blocks thereby forming a continuous air passage around said corner.
9. A corner construction for a wall built of blocks arranged in courses one above the other comprising hollow blocks, one of said blocks constituting an outside corner piece and having a projection extending rearwardly of the exposed faces thereof, one of said exposed faces having a length substantially equal to the thickness of the wall, the other of said exposed faces having a length approximately twice that of the first 65 named side, and two additional blocks having faces which meet to form the inside corner of the wall and each having a projection spaced from the projection of said outside corner piece to form an air space around the corner.
10. A corner construction for a wall built of blocks arranged in courses one above the other comprising hollow blocks, one of said blocks constituting an outside corner piece and having a projection extending rearwardly of the exposed faces thereof, one of said exposed faces being substantially twice as long as the other, and 70 two additional blocks having faces which meet to form the inside corner of the wall and each having a projection spaced from the projection of said outside corner piece to form an air space therewith, the outside corner piece of one of said 75

- courses being inverted and at a horizontal angle of substantially ninety degrees with respect to the corner pieces of the course next thereabove and next therebelow.
- 5 11. A corner construction for a wall built of blocks arranged in courses one above the other comprising hollow blocks, one of said blocks constituting an outside corner piece and having a projection extending rearwardly of the exposed 5 faces thereof, one of said exposed faces being longer than the other thereof, that part of the projection extending rearwardly of the longer of said faces forming an acute angle therewith, and two additional blocks having faces which 10 meet to form the inside corner of the wall and each having a projection extending from the exposed face thereof, both projections of said two blocks being spaced from the projection of said outside piece with the projection of one of said 15 two blocks paralleling that part of the projection of the outside blocks which forms an acute angle with the longer exposed face thereof, the outside corner piece of one of said courses being inverted and at a horizontal angle of ninety degrees with respect to the corner pieces of the 20 course next thereabove and next therebelow.
12. A corner construction for a wall built of blocks arranged in courses one above the other comprising hollow blocks, one of said blocks constituting an outside corner piece and having a 25 projection extending rearwardly of the exposed faces thereof, one of said exposed faces being substantially twice as long as the other, and two additional blocks having faces which meet 30 to form the inside corner of the wall and each having a projection spaced from the projection of said outside corner piece to form an air space therewith, the outside corner piece of one of said courses being inverted and at a horizontal angle of substantially ninety degrees with respect to the corner pieces of the course next thereabove and next therebelow, one of said two additional blocks being substantially twice as long as the other, the two additional blocks of one course alternating in position with those of the course next thereabove and therebelow.
- 45 13. A wall construction comprising a plurality

of blocks laid in courses one above the other, each of said courses comprising inside and outside blocks each having projections extending inwardly of the wall from the exposed faces thereof, said projections being staggered longitudinally of the wall and spaced laterally of each other to form an air space therebetween continuous along sidewalls and around corners, the blocks of one course being longitudinally staggered with respect to the blocks next thereabove and next therebelow, and mortar joints interlocking the projections of one block with the projections of two blocks thereabove and two blocks therebelow.

14. A wall construction comprising a plurality 15 of blocks laid in courses, one course above the other, each of said courses comprising an inside row and an outside row of blocks, those of said blocks which form an uninterrupted wall being of hollow triangular shape in top plan view 20 with the blocks of one of said rows horizontally staggered and laterally spaced from the blocks of the other row thereby forming a continuous air space between said rows, and a block for terminating one of said rows at equal length with the 25 other having one side equal in length to substantially half the length of one of said triangular blocks and having a projection extending from one end thereof substantially parallel to the projection of the block in the other row adjacent thereto but of shorter length than the 30 adjacent projection.

15. A wall construction comprising blocks arranged in courses one course above the other, each of said courses comprising a double row 35 of horizontally spaced longitudinally staggered blocks triangular in top plan view, and a terminating block for one of said rows of V-shape in top plan view with one branch thereof shorter than the other, the blocks of one course being 40 horizontally staggered with respect to the blocks of the courses next thereabove and next therebelow, said V shaped block alternating in position as to said rows in the courses next thereabove and next therebelow.
